UNITED STATES PATENT OFFICE.

WALTER E. WOOD, OF ROCHESTER, NEW YORK, ASSIGNOR TO ELWOOD COAL SERVICE,
OF ROCHESTER, NEW YORK.

COAL-SHIELD.

1,239,549.

Specification of Letters Patent.

Patented Sept. 11, 1917.

Application filed March 24, 1915. Serial No. 16,822.

To all whom it may concern:

Be it known that I, WALTER E. Wood, a citizen of the United States, residing at Rochester, in the county of Monroe and State of New York, have invented a new and Improved Coal-Shield, of which the following is a specification.

My invention relates to devices used for preventing injury to the side of a house, the 10 coal window and the lawn adjacent thereto when putting coal into the cellar.

The usual method of housing coal is by means of a chute extended through a cellar window, the coal being shoveled from a 15 wagon directly onto the chute or carried thereto in baskets or bags. Coal is heavy and it is quite impossible, even though skilfully handled, to put a supply into a cellar without marking the casing of the coal window or the house itself. Furthermore, pieces 20 thereof fall on the grass and are hard to get out without leaving marks of work that disfigure the lawn; while dust accumulates on the window casing and is also carried 25 into the cellar by currents of air through the open window.

It is the object, then, of this invention to provide a shield that will protect the side of the house and casing of the coal window 30 from dust and against being marked, that will cover the ground beneath the coal chute, and that will tend largely to prevent dust being driven through the cellar.

I accomplish these objects by making a 35 shielding device such as illustrated in the accompanying drawings, in which,—

Figure 1 shows in perspective view a coal chute and shield in operative position; Fig. 2, a view of the chute and shield as seen 40 from the inside of a cellar window through which the chute is extended; Fig. 3, a detail showing in side view means used for holding the shield in place against a house; and Fig. 4, a view from the rear, with respect to 45 Fig. 1, of a portion of the shield showing the opening therein through which a chute engages and the protecting flaps, such flaps being turned back against the body portion of the shield.

50 Similar reference characters refer to similar parts throughout the several views.

1 represents the side of a house, 2, the frame of a cellar window and 3 the window casing. At 4 is seen a coal chute supported 55 at its outer end on suitable standards or

legs 5 and extending through the cellar window.

The shield is made, preferably, of strong sail canvas and comprises a main body portion 6 having an opening 7 formed therein 60 through which the chute 4 engages, such opening being preferably, although not necessarily, of rectangular conformation and when so formed is provided with top and bottom flaps 8 and 9, respectively, and side 65 flaps 10, all of which are stitched along their inner edges to the body portion 6 of the shield. These flap members are wider at their outer than at their inner ends, for the purpose later to be explained, and are reinforced by having hems 11 formed along 70 their side and outer edges.

When the shield is in use, the body portion 6 thereof is held against the side of a house 1 by means of comparatively heavy 75 bars or rods 12 placed in an inclined position with their lower ends in the ground or on the side walk 13 and their upper ends engaging the top of the shield to hold it in place. In order that these rods may be prevented from accidentally coming directly in contact with the house, it is preferable to form hooks 14 at their upper ends adapted to engage suitable eye members 15 secured to the shield at approximately six or eight 80 inches from the top and side edges thereof.

The canvas forming the body of the shield may conveniently be of sufficient length to cover the ground beneath the chute 4 and to extend beyond the outer end thereof, and, if 85 desired, an extension section 16 may be added thereto.

The lower flap 9 engages under the chute and covers the window sill, the side flaps 10 protect the sides of the casing 3, while the 90 top flap 8 rests on the side flanges of the chute 4, thus being held out of the path of the descending coal, and protects the window 2; and all of the flaps, especially the top one 8, tend largely to prevent dust arising from the descending coal from being driven by currents of air into the cellar. The flaps are made flaring so that the side edges will engage in overlapping relation to prevent dust from getting therebetween and 100 to better enable the flaps to retain their proper positions.

When the chute 4 has been removed, the canvas lying on the ground is picked up and coal that has fallen thereon dumped through 110

the window, after which the entire shield is folded up so as to occupy but little space in the wagon.

It is believed that from the foregoing the 5 construction, manner of using and purpose of the coal shield is sufficiently clear to call for no further description herein.

What I claim is:

1. A device of the character and for the 10 purpose described comprising a shield made of suitable flexible material and having an opening therein for receiving a coal chute, flap members flexibly connected to the shield along the edges of said opening and 15 adapted to cover the casing of a window and to be held in extended position by a chute extended through said opening and said window, and means for removably sup-

porting said shield against the side of the house.

2. A device of the character and for the purpose described comprising a shield made of suitable flexible material and having an opening therein for receiving a coal chute, flap members wider at their outer than at 25 their inner ends flexibly connected to said shield along the edges of said opening and adapted to cover the casing of a window and to be held in extended position by a chute 30 extended through said opening and said window, and means for removably supporting said shield against the side of the house.

WALTER E. WOOD.
